UNITED STATES PATENT OFFICE.

ALONZO ALDRICH, OF BELOIT, WISCONSIN.

MACHINE FOR MAKING PAPER.

Application filed September 15, 1922. Serial No. 588,332.

My invention relates to machines for making paper.

The object of the invention is to provide a simple, practical and efficient machine of the class specified.

In the accompanying drawings, Fig. 1 is a side elevation of a paper making machine embodying my present invention;

Fig. 2 is a plan view of the same.

Referring to the drawings, I show a machine having a pond 1 for the pulp from which the paper is to be made. Also a rotatable cylinder mold 2 on which the paper is to be made, said wheel having its axle 3 mounted on frames 4-4. A pipe or conduit 5 leads from pond or tank 1, underneath cylinder mold 2, and thence up at 5^a to a discharge box 6 located at one side of forming cylinder 2, with its discharge side 7 shaped like and close to said forming cylinder. The pulp from pond 1 feeds up in section 5^a, as shown by arrows, and thence through box 6 to roll 2, and onto the same. Within box 6 there are preferably sloping vanes 8-8 inclined to surface of cylinder 2, so as to give pulp a sidewise movement to improve fiber arrangement of paper.

A return pipe 10 for pulp leads down from box 6, and a vat or tank 11 is located 30 below cylinder 2 to receive water coming down pipe 10. Another pipe 12 extends up from tank 11 and thence over to pond 1, and a pump 13 pumps the water and pulp from tank 11 back to pond 1.

An apron 14, of felt or like material runs around couch roll 15, whose axle 16 is provided with an adjustable mounting 17 to permit adjustment of roll 15. Felt 14 travels back between press rolls 18-18 in the usual manner, the under side of felt returning around guide rolls 19 and 20, and necessary number of like rolls.

Thus the pulp will flow through box 6 and onto cylinder 2, this cylinder being the usual cylinder mold construction, and will form a film or layer on the latter which becomes the endless sheet of paper, and this film or layer is carried upwardly on and by cylinder 2, so that it adheres to felt 14 and travels along with same, around couch roll 15 and thence between press rolls 18, after which it is separated from felt 14 as usual, and thence through other desired number of press rolls.

It will be seen that the pulp is applied to the upper part of roll 2, close to felt 14,

so that pulp need be lifted but little before meeting felt 14, and consequently pulp has little opportunity to slide down surface of roll 2 and a highly efficient operation is secured.

It will be understood that changes and modifications may be made without departing from the spirit of the invention.

What I claim is:

1. A paper making machine comprising a rotary forming member and means for feeding the pulp to a part of the exterior surface of said member at an oblique angle relatively to the direction of rotation of the rotary member.

2. A paper making machine comprising a rotary forming cylinder and a discharge box for discharging pulp to the surface of the cylinder, said box having a concave end 75 corresponding to the curvature of the cylinder and extending a substantial distance along the same, said box being provided with inclined vanes for directing the pulp upon the cylinder at an inclination. 80

3. A paper making machine comprising a rotary forming member, a discharge box for feeding pulp to said member, a pond, a pipe connection between the pond and discharge box, the latter being located to discharge pulp on upper part of rotary member, a tank below the rotary member, a discharge pipe from discharge box to said tank, a connection from said tank to said pond, and a pump for forcing liquid from 90 the tank to the pond.

4. A paper making machine comprising a rotary forming member, a discharge box for feeding pulp to said member, a pond, a pipe connection between the pond and discharge box, the latter being located to discharge pulp on upper part of rotary member, and means for directing the flow of pulp to said rotary member at an angle. 95

5. A paper making machine comprising a 100 rotary member, a discharge box for feeding pulp to said member, a pond, a pipe connection between the pond and discharge box, the latter being located to discharge pulp on upper part of rotary member and being 105 about on a level with the top of the pond, and a felt running to the top of the rotary member and taking paper film from same.

6. A paper making machine having a rotary forming member, means for feeding 110 pulp to said member, and a drain for draining excess pulp from the forming member,

said drain comprising a downwardly extending pipe arranged in proximity to the area of the forming member to which the pulp is applied.

5 7. A paper making machine comprising a rotary forming member, a feed box having a discharge opening for discharging pulp to an area of said forming member and a downwardly extending drain pipe located 19 at one end of said feed box.

8. A paper making machine comprising a rotary forming member, means for feeding pulp to a portion of the exterior surface of said member, said feeding means being a 15 portion of a circulatory system by which the pulp fed to the cylinder is forced upwardly and the surplus pulp drained downwardly.

9. A paper making machine comprising a 20 rotary forming member, means for feeding pulp to a portion of the exterior surface of said member, said feeding means being a portion of a circulatory system by which the

pulp fed to the cylinder is forced upwardly and the surplus pulp drained downwardly, 25 said system including a discharge box having a discharge opening for discharging pulp to the cylinder, an upwardly arranged feed pipe for feeding pulp to said box, and a downwardly extending drain pipe for 30 withdrawing and draining surplus pulp.

10. A paper making machine comprising a rotary forming cylinder, a discharge box for feeding pulp to said cylinder, a pond, a pipe connection between the pond and the 35 discharge box, a tank below the rotary cylinder, a pipe extending from the discharge box down to said tank, a second pipe extending from the tank to the pond, and a pump for circulating liquid through said 40 last mentioned pipe.

In witness whereof, I hereunto subscribe my name this 1st day of September, A. D., 1922.

ALONZO ALDRICH.
